United States Patent

Des. 235,742
Patented July 8, 1975

235,742

AUDIOMETER OR SIMILAR ARTICLE

Erwin H. Rock, Beden Ave., Ardsley, N. Y. 10502, and
Irwin Klar, 5 Assembly Court, New City, N.Y. 10956

Filed Jan. 22, 1974, Ser. No. 435,532

Term of patent 14 years

Int. Cl. D10—05

U.S. Cl. D10—46

FIG. 1.

FIG. 2.

FIG. 3.

FIG. 4.

FIG. 1 is a left front perspective view of an audiometer or similar article showing our new design;

FIG. 2 is a top plan view thereof;

FIG. 3 is a left side elevational view thereof, the right side being a mirror image thereto;

FIG. 4 is a left side elevational view thereof as resting on its back.

The rear and bottom of the audiometer not shown are substantially plain and unornamented.

We claim:

The ornamental design for an audiometer or similar article, substantially as shown and described.
